WAVE FILTER.

Application filed August 20, 1925. Serial No. 51,361.

This invention relates to wave filters and more particularly to methods of terminating wave filters whereby advantageous transmission characteristics may be secured.

5 In the design of broad band wave filters it has heretofore been the common practice to proportion the wave filter in accordance with the impedance of the lines or apparatus to which it is connected so as to secure the 10 most uniform transmission over the whole transmitting range.

In many applications of wave filters to selective transmission systems, it is not necessary that transmission within the band 15 be uniform at all frequencies, and in such cases it has been found that advantages may be secured both in respect of economy of materials and of selectivity of transmission by suitably proportioning the relative impedances of the filter and its connected apparatus.

An important application of the invention, is in the construction of wave filters for connecting carrier wave signalling apparatus to high voltage power lines, the 25 advantage gained being a great reduction in the capacity of the high voltage coupling condensers and a corresponding reduction in their cost.

30 A general object of the invention is to control the characteristics of frequency selective systems by proportioning the impedance of wave filters by means of which the frequency selectivity is secured.

35 Another object is to reduce the cost of coupling circuits for supplying high frequency signalling waves to high voltage power lines.

Another object is to improve the transmission characteristics of coupling circuits in 40 duplex, or two-way, power line carrier telephone systems.

A feature of the invention lies in the proportioning of wave filters to have impedances 45 greatly different from the impedances of the apparatus to which they are connected.

In the detailed description that follows, certain theorems of wave transmission will be discussed by means of which the nature 50 of the invention may be more clearly understood. One application of the invention, namely, to power line carrier wave signalling systems will also be described. It is to be understood, however, that the invention is 55 not limited to this particular application,

but only by the scope of the subjoined claims.

Of the accompanying drawings, Fig. 1. represents in schematic form a transmission system in which the invention is embodied; 60

Figs. 2, 3 and 4 are theoretical diagrams for explanation purposes; and

Fig. 5 illustrates the nature of the modification of the transmission characteristic obtained by the application of the invention. 65

The system of Fig. 2 represents in schematic form a broad class of wave transmission systems, in which two terminal networks are linked together through a passive linear transducer, a wave source being included in 70 one of the terminal impedances.

A passive linear transducer is defined as an electrical network having two input terminals and two output terminals and a structure such as that so far as these terminals are concerned the currents are linear 75 functions of the potential differences, and having no internal source of energy. A feature of such a system is that the principle of superposition holds as also does the principle of reciprocity.

In Fig. 2 the part included within the dotted rectangle represents a passive linear transducer, the input terminals of which are designated by the letters a a and the output 80 terminals by b b . The transducer is connected between a sending end impedance Z_a , in which is generated an E. M. F. E_a , and a receiving end impedance Z_b .

In the general case the structure within 85 the dotted lines is restricted only to conform to the definition given above. It may be, for example, a long transmission line, or a wave filter, or it may comprise any arbitrary combination of invariable elements. 90 The terminal impedances may likewise represent any kind of wave generating or wave receiving apparatus.

The input and the output currents, denoted 95 respectively by I_a and I_b , corresponding to the E. M. F. E_a , may be computed in terms of the terminal impedances and the impedances of the individual elements constituting the transducer, but it is more convenient and more illuminating to determine these 100 currents from a set of much more general properties of the transducer to which the name image parameters has been given.

The image parameters comprise the image 105 impedances, the transfer constant, and the 110

directional transfer constants. The image impedances are two in number, corresponding to the two pairs of terminals. In the analysis that follows they are denoted by W_a and W_b for the input and output terminals respectively. They are defined as the impedances by which the transducer may be terminated without the introduction of reflection loss. In other words if the terminal impedances Z_a and Z_b are equal to the image impedances W_a and W_b respectively, then the impedances of the two parts of the system to right and to left of terminals a will be equal to W_a , and a similar condition will hold at the terminals b .

The directional transfer constants are also two in number, one, designated by T_{ab} , applying to wave transmission from terminals a to terminals b , and the other, designated by T_{ba} , applying to wave transmission in the opposite direction.

The directional transfer constant is defined as the natural logarithm of the ratio of the input current to the output current of the transducer when the terminal impedances are equal to the image impedances. Expressed mathematically

$$T_{ab} = \log_e \left(\frac{I_a}{I_b} \right), \quad (1)$$

when transmitting from terminals a to terminals b , and

$$T_{ba} = \log_e \left(\frac{I_b'}{I_a'} \right), \quad (2)$$

when transmitting from terminals b to terminals a , the currents in the second case being distinguished from those of the first case by prime marks. The limitation as to the terminal impedance is implied in each case.

The remaining parameter, the transfer

$$I_b = \frac{E}{\sqrt{4Z_a Z_b}} \cdot \frac{\sqrt{4W_a Z_a}}{W_a + Z_a} \cdot \frac{\sqrt{4W_b Z_b}}{W_b + Z_b} \cdot \frac{e^{-T}}{1 - r_a r_b e^{-2T}}. \quad (5)$$

The first factor in equation 5 gives the current that would flow if the two terminal impedances were connected together through an ideal impedance matching transformer. It is useful to consider this as a standard reference current with respect to which the gain or loss due to the inserted apparatus may be measured. The second and third factors give the separate reflection losses at the junctions to the terminal impedances. The factor e^{-T} is the transfer factor, and the divisor $(1 - r_a r_b e^{-2T})$, which has been called the "interaction factor", represents the summation effect of repeated reflections from one end of the system to the other.

If the reflection coefficients r_a and r_b are both made equal to zero, as may be done by making Z_a equal to W_a and Z_b equal to W_b , the third and fourth factors and the interac-

constant T , is equal to the arithmetic mean of T_{ab} and T_{ba} , or

$$T = \frac{T_{ab} + T_{ba}}{2}. \quad (3)$$

It is important to note that the quantities thus defined are parameters of the transducer itself without regard to the impedances to which the transducer may be connected. They serve therefore to describe the properties of the transducer in broad terms.

For a complete analysis of the transmission through a transducer system and for a description of important relationships between the image parameters and other coefficients of a network, reference is made to the technical paper entitled "Transmission Characteristics of Electric Wave Filters" by Otto J. Zobel, published in the Bell System Technical Journal, Vol. III, No. 4, October, 1924, and particularly to Appendices I and II thereof.

The following equation, given by Zobel, expresses the received current I_b in terms of the image parameters.

$$I_b = \frac{2E_a \sqrt{W_a W_b} e^{-T}}{(W_a + Z_a)(W_b + Z_b)(1 - r_a r_b e^{-2T})} \quad (4)$$

Where r_a and r_b , the current reflection coefficients at terminals a and b , are respectively

$$r_a = \frac{W_a - Z_a}{W_a + Z_a}$$

and

$$r_b = \frac{W_b - Z_b}{W_b + Z_b}$$

Equation 4 may be rewritten in the following form in which the component losses are effectively displayed.

$$I_b = \frac{E}{\sqrt{4Z_a Z_b}} e^{-T} \quad (6)$$

tion factor become unity and the equation reduces to

If the matching of the impedances is performed at one end only, the interaction factor still reduces to unity, but only one reflection loss factor, namely that corresponding to the matched end of the system, will reduce to unity.

Matching the impedances at both ends has the effect of eliminating all reflection losses, including that part which may be attributed to the inequality of the terminal impedances, and leaving only the inherent loss of the transducer as expressed by its transfer constant.

Since the definition of the transfer con-

stant, as the mean of the two directional transfer constants, may not readily convey an idea of its physical nature, it may be stated that the transfer constant determines the energy, or volt-ampere, attenuation in the system. It can be shown that when the image condition holds at the terminals the volt-ampere attenuation is given by the equation

$$\frac{V_a I_a}{V_b I_b} = e^{sT} \quad (7)$$

in which V_a and V_b are the voltages at terminals a and b respectively. This relationship follows readily from equations 71 and 72 given in the above mentioned paper.

In most practical cases the image impedances are not constant quantities but vary with frequency in such manner that it is difficult, if not impossible, to construct terminal apparatus having impedances to match the image impedances at more than a few selected frequencies. The common practice is to secure a good approximation to equality over the important frequency ranges and the degree of equality secured is reflected in the closeness with which the transmission characteristic of the whole system corresponds to that of the transducer alone as defined by equation 6.

The image parameters are related by simple formulae to the open circuit and the short circuit impedances of the transducer. The derivation of the relationships is given in the article by Zobel already referred to, and the results are therefore given here without the mathematical development.

Let X_a and Y_a be the impedances of the transducer measured at terminals a with terminals b open-circuited and short-circuited respectively, and let X_b and Y_b be the corresponding impedances for terminals b , then

$$\left. \begin{aligned} W_a &= \sqrt{X_a Y_a}, \\ W_b &= \sqrt{X_b Y_b}, \\ \text{and} \quad T &= \tan h^{-1} \sqrt{\frac{Y_a}{X_a}} = \tan h^{-1} \sqrt{\frac{Y_b}{X_b}}. \end{aligned} \right\} \quad (8)$$

With the help of these formulae the image parameters may be determined from measurements of impedance made on the transducer alone, or by computation from the coefficients of its structural elements.

Electric wave filters constitute a special class of transducers characterized by being composed of a chain of networks each of which includes only reactive impedance elements. In practice, of course, it is not possible to construct impedance elements entirely free of resistance, but it has been found as the result of much experience that the properties of a purely reactive system are very closely approximated so long as

the resistances of the elements do not exceed one fiftieth of their reactances.

The well-known property of wave filters is their ability to transmit wave energy freely within certain definite bands of frequencies and to attenuate the energy at all other frequencies.

The limits of the transmission bands may be determined by an examination of the image impedances of the filter. Since the filter is assumed to be composed of purely reactive elements it follows that the open circuit and short circuit impedances must also be pure reactances. The image impedances W_a and W_b however are not necessarily pure reactances but may be either pure reactances or pure resistances. W_a is a pure reactance if X_a and Y_a are reactances of the same sign, that is if both are inductive together or capacitive together. On the other hand if X_a and Y_a are of opposite sign W_a is a pure resistance. This follows from a consideration of equation 8. In addition, since

$$\frac{Y_a}{X_a} = \frac{Y_b}{X_b}, \quad (9)$$

it follows that W_a and W_b are both reactive together and resistive together.

If now the filter is assumed to be terminated in its image impedances, then for certain frequency ranges the whole system including the terminals is reactive and at certain other frequency ranges it is resistive. In the first case, there can be no transmission of energy, but only a surging back and forth of energy from the input to the output of the system; whereas, in the second case, energy may be freely transmitted through the system and absorbed in the receiving impedance.

The transmission bands therefore coincide with the frequency ranges for which the image impedances are pure resistance. If a transducer is symmetrical in its schematic form with respect to the direction of transmission, the two image impedances have the same value. Similar symmetrical transducers can therefore be connected in tandem without introducing reflection losses at the junction points, and the image impedances of the whole chain will be the same as those of the individual networks.

Uniform wave filters are constituted by such a chain of symmetrical sections, the common schematic forms of the sections being the well-known T , and π networks. The T sections are sometimes called "mid-series" sections, and the π sections, "mid-shunt", in view of the process of division whereby they may be derived from an intended uniform wave filter. The image impedances of the symmetrical sections are equal to their mid-section iterative impedances, and the transfer constant is equal to the propagation con-

stant, in terms of which the characteristics of the filter are commonly defined.

For the purpose of obtaining different types of termination it is common practice to include a half section in a wave filter network, the half of a symmetrical $\mathbf{T}$ section being identical with the half of a corresponding symmetrical π section.

In Fig. 2, for example, the transducer is part of a uniform wave filter having series branches and shunt branches of impedances Z_1 and Z_2 respectively, and comprises one symmetrical π section and one half section. The half section, being unsymmetrical, has two image impedances, one equal to that of the symmetrical π section and one equal to that of the corresponding symmetrical $\mathbf{T}$ section.

The two image impedances of the system may be computed in terms of Z_1 and Z_2 with the help of equations 8, and when this is done it is found that their ratio is given by

$$25 \quad \frac{W_b}{W_a} = 1 + \frac{Z_1}{Z_2} \quad (10)$$

Since Z_1 and Z_2 are both reactive the ratio is a simple numeric quantity the value of which may be equal to, less than or greater than unity depending upon the respective values of Z_1 and Z_2 at different frequencies.

It appears then that a wave filter comprising an odd number of half sections of uniform $\mathbf{T}$ or π networks may be adapted to connect two unequal terminal impedances so that there will be no reflection loss in the system at certain definite frequencies.

In accordance with the present invention this principle is employed in the design and construction of transmission systems to secure advantageous results.

In Fig. 1 is shown in simplified schematic one terminal of a power line carrier telephone system in which the invention finds application. The principal units of this system are a speech frequency line 1, 1, a two-way carrier translating system 2, a coupling filter 3, and a high voltage power line 4, 4.

Only the essential elements of the system are shown, the detail arrangements of the circuits being capable of many variations, one of which is disclosed in the co-pending application of Wallace V. Wolfe, Serial No. 664147 filed September 22, 1923.

The carrier translating system 2 comprises a bridge coil 5 and line-balance 6, whereby directional separation of the speech currents is secured. Speech currents outgoing to the line 4, 4 enter the modulator-amplifier 7 wherein they are caused to modulate a high frequency carrier wave in any well known manner. The modulated high frequency wave is selected by a band pass wave filter 8 and transmitted to the terminals 9 of cou-

pling filter 3, through which it is transmitted to the power line 4.

Waves incoming from the power line also pass through the coupling filter and on reaching terminals 9 are diverted to the receiving channel of the translating system by a band filter 10 of appropriate range. From filter 10 the incoming modulated waves pass to detector 11 in which the speech waves are reproduced and finally transmitted to the telephone line 1 through bridge coil 5.

To permit separation in the translating system of the outgoing and the incoming carrier waves they must necessarily have different frequencies, and the transmission range of coupling filter 3 must be great enough to permit both waves to pass freely. In one practical embodiment it has been found satisfactory to use carrier frequencies of 75 K. C. and 105 K. C. for the two waves and to provide for the transmission in the coupling filter of a band of frequencies extending from 70 K. C. to 110 K. C.

The coupling filter 3 is of the type described in U. S. patent to G. A. Campbell No. 1,227,113 issued May 22, 1917. Each series branch consists of a simple resonant circuit and each shunt branch consisting of a simple anti-resonant circuit, the frequencies of resonance and anti-resonance being equal. At the end next to the power line the filter terminates in series branches in which are included high voltage condensers 12 designed to withstand the high voltage of the power line. At the end next to the translating apparatus the filter terminates in a shunt branch.

The complete structure includes one π section and one half section, corresponding to the arrangement shown in Fig. 2, but additional sections may be added as desired.

The image impedances of the filter are plotted in Figs. 3 and 4 as functions of the frequency. Fig. 3 refers to the power line end of the filter and Fig. 4 to the opposite end. The portions of the impedance curves shown dotted represent reactances and the band limits are indicated by f_1 and f_2 at which points the impedances change from reactance to resistance.

Within the band image impedance of the $\mathbf{T}$ section, or of the mid-series terminated end, is zero at each band limit and reaches a maximum at an intermediate frequency. The image impedance of the π section, or mid shunt termination, passes through a reciprocal set of valves being infinite at the band limits and reaching a minimum at an intermediate frequency. The maximum impedance of the $\mathbf{T}$ section is equal to the minimum impedance of the π section and occurs at the same frequency, namely, the geometric mean of the band limiting frequencies.

The impedance at this mean frequency

has come to be regarded as the most characteristic impedance of a wave filter and it has heretofore been the common practice to design filters so that this impedance is equal to that of the terminating apparatus. The term nominal impedance is used here to define this special value of the image impedances. In practically all cases it is found that the value of the nominal impedance is expressed by a very simple formula involving the constants of the elements only. For the special cases represented by low-pass filters and high-pass filters, one band limit is at zero frequency or at infinity, and the geometric mean frequency corresponding to the nominal impedance is also at zero or infinity.

The impedance of a power line, or other transmission line, is generally fairly constant and of a comparatively low value. On the other hand, the impedance of a modulating or amplifying device is generally much greater, so that in superimposing modulated carrier currents upon a power line a stepping down of the voltage corresponding to the ratio of the impedances is necessary.

If the filter is designed so that its nominal impedance matches the terminal impedances, it is necessary to proportion the filter to the power line impedance, since it would not be practicable to interpose a transformer between the filter and the power line. Matching the impedance of the filter to that of the translating apparatus would then be accomplished by inserting a transformer of appropriate transformation ratio.

In accordance with the invention, however, the filter is designed to have a nominal impedance intermediate in value between the two terminal impedances, preferably several times greater than the power line impedance. In relation to the image impedances indicated in Fig. 3, and Fig. 4, the power line impedance would be represented by the line DD¹ in Fig. 3 and the impedance of the translating apparatus by GG¹ in Fig. 4.

Considering the curves of Figures 3 and 4 it will be seen that the terminal impedances, i. e., of the line and translating apparatus, are matched by the filter at points *e* and *h* which are fairly close to the band limits and that there is a considerable disparity in the impedances at the middle of the band.

The effect of these proportions on the transmission characteristic will be considered first. This is illustrated in Fig. 5 in which the heavy curves 13 represent the transfer constant of the filter for frequencies throughout and close to the transmission band, dotted curve 14 represents the overall transmission characteristic of the system that is obtained when the filter is designed to match the terminal impedances at

the mean frequency in the band, and curve 15 is the corresponding characteristic obtained by matching the unequal terminal impedances to the filter impedances at frequencies close to the band limits.

The quantities that are compared to give the transmission characteristics 14 and 15 are the actual output currents I_b as given by equation 5 and the reference value given by

$$I_{b,0} = \frac{E}{\sqrt{4Z_s Z_b}}$$

which was discussed in connection with equation 5. To permit of comparison with the filter transfer factor the transmission ratio is defined as the natural logarithm of the ratio

$$\frac{I_{b,0}}{I_b}$$

Characteristic curve 14 shows most efficient transmission at the middle of the band accompanied by a marked rounding-off near the band limits due to terminal reflection losses. Curve 15 shows that the reflection losses have been greatly reduced near the band limits and increased at the middle of the band. Curve 15 also shows that the steepness of the characteristic at the edges of the band has been greatly increased.

The increased efficiency of transmission near the band limits permits the two carrier waves of the system of Fig. 1 to be more freely transmitted, which is a desirable condition in a two-way signalling system of the type described.

The reflection loss that is thrown to the middle of the band has a maximum value equal to that due to the disparity of the two terminal impedances and it is found that impedances differing in the ratio of 10 to 1 may be linked together without increasing this loss to a degree that would noticeably distort transmitted speech.

The effect of adding additional sections to the filter is to introduce some slight ripples into the portion of curve 15 lying within the transmission band but not sufficient to change its general form.

The advantageous result in the filter construction, due to the application of the invention, lies in the reduction of the capacity of the high voltage condensers 12. As the filter impedance is increased the impedance of each branch is proportionately increased, this being achieved by making the inductances proportionately greater and the capacities smaller in an inverse proportion.

This may be illustrated by citing the values computed for a typical system.

Let it be assumed that the power line impedance is 400 ohms and that the impedance of the translating apparatus is 4000 ohms, these figures being close to values found in actual practice.

If the coupling filter is designed to have a nominal impedance of 400 ohms and to have band limits at 70 K. C. and 110 K. C. it is found that the capacity of condensers 5 should be equal to .004 microfarads. By increasing the filter impedance to 1600 ohms the coupling condenser capacities are reduced to one quarter, or .001 microfarads.

The coupling condensers may be required 10 to isolate line voltages as high as 120 kilovolts in which case they become very large and costly even for small capacities.

Some idea of the difficulties involved in the construction of these high voltage condensers 15 may be gained from the fact that condensers of .003 microfarad capacity built to operate on a 120 kilo-volt line weighed 8000 pounds and occupied a space of 5 feet in diameter and 12 feet high. The economic advantage 20 of using the smallest possible capacities is apparent.

The foregoing description and discussion 25 has related more specifically to the case in which a filter is utilized to interconnect two unequal impedances, the filter being designed to have a nominal impedance of intermediate value. The arrangement is, however, capable of variation without substantially modifying the results obtained.

30 For example the two terminal impedances may be equal and of low value to begin with. In this case the filter may be terminated in series branches at both ends thereby establishing at both ends the relationship between 35 the image and the terminal impedances that is shown in Fig. 3. By making the filter impedance at the mean transmission frequency high relatively to the two terminal impedances the advantages already described 40 may be secured.

In another application the filter may be matched at the mean frequency to the greater of two unequal impedances and at frequencies close to the band limits to the smaller 45 impedance. In this way the reflection losses instead of occurring all at the band edges or all at the centre of the band are divided in a fairly uniform manner throughout the band.

Other possible variations naturally suggest 50 themselves in which the basic principle of the invention is retained, namely, that the transmission loss within the frequency band to be transmitted is removed at least in part from the edges of the band to the 55 centre by designing the filter so that its nominal image impedance is greatly different from one or both of the terminal impedances.

What is claimed is:

1. A frequency selective wave transmission 60 system comprising a wave filter having two pairs of terminals and having transmission devices representing terminal impedances connected to said pairs of terminals, said filter being so proportioned that the 65 image impedance at one pair at least of its

terminals is greatly different from the terminal impedance connected thereto throughout the major part of the range of free transmission and is equal to the connected terminal impedance of a frequency close to a 70 limit of free transmission whereby reflection loss is eliminated in the neighborhood of said limit.

2. A frequency selective wave transmission system comprising a broad band wave filter 75 having two pairs of terminals and having transmission devices representing terminal impedances connected to said pairs of terminals, said filter being so proportioned that its image impedances at said pairs of terminals 80 are greatly different from the impedances of said terminal apparatus throughout the major portion of the filter transmission band and are equal to the connected terminal impedances at frequencies close to the 85 limits of the transmission band, whereby reflection loss is eliminated in the neighborhood of the band limits.

3. A frequency selective wave transmission system comprising a broad band wave 90 filter, two pairs of terminals therefor, and transmission devices representing terminal impedances, connected to said terminals, one of said terminal impedances being much greater than the other, and said filter being 95 so proportioned that its nominal image impedance has a value intermediate between the terminal impedances and that at frequencies close to the band limits the image impedances are equal to the terminal impedances, whereby reflection loss is eliminated at frequencies close to the band limits.

4. In a frequency selective transmission system, a broad band wave filter, and transmission devices representing terminal impedances connected thereto, one of said terminal impedances being much greater than the other and said filter having a nominal impedance at the mid-band frequency intermediate between said terminal impedances 110 and having series and shunt terminations at the ends adjacent to the low and the high terminal impedances respectively whereby the filter image impedances are matched to the terminal impedances at frequencies close 115 to the band limits.

5. In a power line communication system, power conductors, signal translating apparatus adapted for the transmission and reception of signals in two carrier wave channels, and a broad-band wave filter connected between said apparatus and said conductors, the image impedances of said wave filter having a nominal value much greater than the impedance of said conductors and having values close to the band limits which match the impedances of said conductors and said translating apparatus, whereby there are provided two frequency ranges of minimum loss close to the band limits, in 120 125 130

which ranges separate signal channels may be located.

6. In a power line communication system, a transmission line adapted to transmit high voltage energy, signal translating apparatus adapted for signalling by means of modulated carrier waves, and a broad band wave filter connected between said line and said apparatus, said filter being terminated adjacent to the transmission line in series branches including condensers and having an image impedance at the line end which greatly exceeds the line impedance at the middle of the band and is equal thereto at frequencies close to the band limits, whereby efficient coupling is secured at selected frequencies by means of low capacity condensers in the terminating branches of the filter.
7. As a coupling element between sections of a wave transmission system having unequal impedances, a broad band wave filter proportioned to have image impedances at its terminals which match the impedances to be coupled at frequencies close to the band limits and differ greatly therefrom at intermediate frequencies within the band, whereby efficient transmission is secured at selected frequency ranges within the band.

In witness whereof, I hereunto subscribe my name this 18th day of August, A. D. 1925.

TIMOTHY E. SHEA.
